UNITED STATES PATENT OFFICE

LINCOLN BARKER, OF NEW YORK, N. Y.

DESIGN FOR A TEXTILE FABRIC

Application filed May 24, 1930. Serial No. 35,753. Term of patent 3½ years.

To all whom it may concern:

Be it known that I, LINCOLN BARKER, a citizen of the United States, residing in New York, in the county of New York, State of New York, have invented a new, original, and ornamental Design for a Textile Fabric, of which the following is a specification, reference being had to the accompanying drawing, forming part thereof.

The figure is a plan view of a piece of

textile fabric showing my new design. A single unit of my design is substantially comprised within the area defined by the indicating dot and dash lines shown on the drawing, the extension of the unit at the left and upper edges being indicated by dotted lines.

I claim:

The ornamental design for a textile fabric substantially as shown and described.

LINCOLN BARKER.
